OTTO STRITTER, OF SCHÖNEBERG, NEAR BERLIN, GERMANY, ASSIGNOR TO AKT. GES. MIX & GENEST, TELEPHON & TELEGRAPHENWERKE, OF SCHÖNEBERG-BERLIN, GERMANY.

ELECTRICAL MEANS FOR PRODUCING SOUND.

1,081,635.

Specification of Letters Patent. Patented Dec. 16, 1913.

Application filed November 9, 1911. Serial No. 659,429.

To all whom it may concern:

Be it known that I, OTTO STRITTER, a subject of the German Emperor, and residing at Schöneberg, near Berlin, Germany, have 5 invented certain new and useful Improvements in Electrical Means for Producing Sound, of which the following is a specification.

My invention relates generally to electrical 10 devices for producing sound and, particularly, to electric horns, and important objects are to provide that a pure note of any desired pitch can be obtained in such devices, and to keep the consumption of current as low as possible.

To these ends, I employ in my improved horn or the like an armature having an automatic interrupter, the arrangement being such that the armature causes the diaphragm 20 to vibrate and permanently tensions the same by means of a regulatable spring. Owing to being thus tensioned, when the diaphragm vibrates it is always connected with the armature and those rattling and 25 hammering accessory noises are avoided which are produced when the connection between the diaphragm and the armature is temporarily broken. By connecting the armature with the diaphragm solely by 30 spring-pressure I obtain the additional advantage that the diaphragm can vibrate freely at right angles to its own plate, so that it is impossible for the same to be distorted and bent. I preferably give the 35 armature the form of a bell-crank lever in order to make the entire sound-producing device as compact as possible. I regulate the pitch by means of an adjustable interrupting device for the armature current.

40 An additional improvement in one form of my invention is the simultaneous employment of the regulatable spring for tensioning the diaphragm as an adjustable interrupting spring, and providing this spring 45 with a regulatable stop. Owing to this arrangement I obtain various advantages. Firstly, at the moment when the spring pressure ceases, thus when the armature current is stopped, the coupling pressure between the armature and diaphragm also 50 ceases; consequently, the diaphragm can swing back with great force so that the note is a specially pure one. Further, without influencing the duration of contact I can 55 permanently tension the diaphragm to any

desired extent. If the stop were not adjustable there is no doubt but that, with a highly tensioned contact spring, the interrupter contact would be shifted in such manner as to be broken when the armature moved a 60 short distance. The consequence of this would be that the vibrations of the diaphragm would be smaller which would undesirably influence the strength of the note, as the permanent tension of the diaphragm 65 is increased. Owing to the adjustability of the stop I am, however, able, when the same is placed low down, to establish the previous duration of contact and with it the like kind of vibration.

70 One illustrative embodiment of my invention and modifications thereof are represented by way of example in the accompanying drawing, wherein:-

75 Figure 1 is a vertical elevation, partly in section, showing the simplest form of my invention comprising a regulatable spring for producing the preliminary or permanent tension and a special interrupting device; Figs. 2 and 3 are like views of modified 80 forms in which the tensioning spring is simultaneously the interrupting spring; the armature in Fig. 2 is angular, while in Fig. 3 a pin or rod is provided between the armature and the diaphragm.

85 The device according to Fig. 1 substantially consists of a sound-box 1 closed at one end by a diaphragm 2 held between rings 3. On the rear of the sound-box and above the diaphragm as shown in the drawing is mounted a plate or bridge 4 on which is secured the automatic interrupter. This comprises an electromagnet 5, an armature 6 and the interrupter contact-piece 7. The armature forms one arm of a two-armed 90 lever which is fulcrumed at 13 and has a second arm 8. The latter arm has in the bottom of its free end a small recess 24. In this rests a pin 23 mounted on an intermediate member or abutment 9 carried by the diaphragm 2. The armature is under the action of a tension spring 25 mounted above the electromagnet on the base thereof. This spring is adjusted in such manner that the lever arm 8 engaging with 95 the pin 23 tensions the diaphragm 2, whereby the diaphragm is bent downward. When the armature is released the contact piece 7 contacts with the contact piece 10 carried by the arm 8. The contact piece 7 is on 100 105 110

the interrupting spring 11 mounted in the support 26. This spring can be adjusted by the screw 12 in such manner that the arm 8 bears firmly against the intermediate 5 abutment 9 so that when the device is in operation hammering movements between the arm 8 and the intermediate abutment 9 or the diaphragm 2 cannot be produced.

Any suitable means may be utilized for 10 operatively connecting the lever arm 8 with the diaphragm 2 or the intermediate abutment 9. The form shown in the drawing, however, is desirable in that the diaphragm may vibrate at right angles to its own plane 15 without being bent or twisted owing to the arm 8 moving in an arc of a circle, this having heretofore frequently led to rupture of the diaphragm at its place of attachment.

In the form according to Fig. 2 no special 20 spring for tensioning the diaphragm is employed. The interrupting spring simultaneously serves this purpose. The interrupting spring 11 is adjusted by the screw 12 in such manner that it presses sufficiently 25 firmly against the lever arm 8, whereby the diaphragm is sufficiently tensioned. For limiting the deflection of the spring 11 I provide the stop 14 which can be adjusted by the screw 15. Both this screw and the 30 screw 12 for adjusting the spring 11 are movable in a common bar 17 mounted together with the spring 11 and the stop 14 in a support 20 having the form of a column fixedly mounted on the bridge 4.

35 The form according to Fig. 3 differs from that according to Fig. 2 only in that the electromagnet 5 is arranged on the plate 4 centrally relatively to the diaphragm. The armature 6 of the electromagnet is connected with a pin 16 which imparts its movement to the diaphragm. Further, the break contact piece 10 is directly on the armature. In addition, the interrupting spring 11 and the stop 14 are arranged in separate supports 21 and 22, respectively, each having a bar 18, 19, respectively, for carrying the adjusting and regulating screws 15 and 12.

In order to start working one of the devices according to Figs. 1 to 3 the interrupting 50 springs 11, the contact pieces 7, 10, the armatures 8, 6 and the winding of the electromagnet 5 are connected in series, whereupon the ends of this circuit are connected to a source of current. The device then 55 operates as follows:—

The armature 6 is attracted by the energized electromagnet 5 whereby the arm 8 depresses the diaphragm 2 by means of the intermediate abutment 9 or the pin 16. In 60 consequence of the elasticity of the spring 11 or 25 the contact 7, 10 is opened. As the circuit is now broken the armature 6 is released until the contact 7, 10 is closed again. This play of the armature 6 and the spring 65 11 or 25 is repeated in very rapid succession,

whereby the diaphragm 2 is vibrated very rapidly. In the forms according to Figs. 2 and 3 the stroke of the spring 11 is limited by the stop 14. If it is wished to produce a higher note the screw 12 must be screwed 70 farther in, whereby the diaphragm is more highly tensioned in consequence of the pressure of the spring being increased. The stop 14 must be adjusted by the screw 15 in such manner that the motion of the 75 spring 11 is checked at the proper moment. Consequently, the adjustable stop 14 enables the make and break contact 7, 10 to be regulated even when the pressure of the interrupting spring 11 on the moving mechanism 80 between the armature and the diaphragm is varied. The circuits between the armatures and the winding of the electromagnet are closed by closing the hand-operated contacts 27 and 28. 85

I claim:—

1. In electrical means for producing sound, the combination with a diaphragm, of an electromagnet, an armature coacting with said electromagnet and operatively engaging said diaphragm, a contact piece carried by said armature, and a tensioned interrupting spring carrying a contact piece normally depressing said first mentioned contact piece and thereby tensioning the diaphragm, the said armature being electrically connected in series with the winding of the electromagnet. 90

2. In electrical means for producing sound, the combination with a diaphragm, 100 of an electromagnet having an armature in the form of a bell-crank lever, an abutment carried by the diaphragm supporting one arm of the armature, a tension spring attached to the other arm of the armature and tending to depress the former arm, the former arm carrying a contact piece, and an interrupting spring carrying a contact piece normally coacting with the former contact piece, the said armature being electrically connected in series with the winding 105 of the electromagnet. 110

3. In electrical means for producing sound, the combination with a diaphragm, 115 of an electromagnet, an armature coacting with said electromagnet and operatively engaging said diaphragm, a contact piece carried by said armature, and a regulatably tensioned interrupting spring carrying a contact piece normally depressing said first 120 mentioned contact piece and thereby tensioning the diaphragm, the said armature being electrically connected in series with the winding of the electromagnet.

4. In electrical means for producing 125 sound, the combination with a diaphragm, of an electromagnet having an armature in the form of a bell-crank lever, an abutment carried by the diaphragm supporting one arm of the armature, a regulatable tension 130

- spring attached to the other arm of the armature and tending to depress the former arm, the former arm carrying a contact piece, and a regulatably tensioned interrupting spring carrying a contact piece normally coacting with the former contact piece, the said armature being electrically connected in series with the winding of the electromagnet.
- 5 10. In electrical means for producing sound, the combination with a diaphragm, of an abutment carried by said diaphragm, an electromagnet, an armature having an arm resting on said abutment, a contact piece carried by said arm, and a tensioned interrupting spring carrying a contact piece normally depressing said first mentioned contact piece and thereby tensioning the diaphragm, the said armature being electrically connected in series with the winding of the electromagnet.
- 15 15. In electrical means for producing sound, the combination of a diaphragm, an abutment carried by said diaphragm, an electromagnet, an armature having an arm resting upon said abutment, a contact carried by the said arm opposite said armature, an interrupting spring, a contact carried by
- 20 25. In electrical means for producing sound, the combination of a diaphragm, an abutment carried by said diaphragm, an electromagnet, an armature having an arm resting upon said abutment, a contact carried by
- 30 35. said spring for coacting with said first mentioned contact, said spring normally acting upon said armature, through said contacts, to tension said diaphragm, and means for adjusting the tension of said spring, substantially as and for the purpose set forth.
- 35 40. 7. In electrical means for producing sound, the combination of a diaphragm, an electromagnet disposed with its core substantially parallel to the plane of said diaphragm, a pivotally mounted armature having one end extending over said diaphragm and adapted to move in a plane substantially perpendicular to the plane of said diaphragm, said arm operatively engaging said diaphragm, a contact carried by said arm of said armature, an interrupting spring, a contact carried by said spring for coaction with said first mentioned contact, and means for tensioning said spring to normally depress said diaphragm, substantially as and for the purpose set forth.
- 45 50. In testimony whereof I affix my signature in presence of two witnesses.
- OTTO STRITTER.
